KEY RETAINER

Rene M. Schupbach, Cranston, R. I., assignor to
Freeman-Daughaday Company, a corporation
of Massachusetts

Application August 20, 1940, Serial No. 353,339

5 Claims. (Cl. 70—459)

This invention relates to a key retainer of the type usually carried by men either loose in the pocket or on the end of a chain; and has for one of its objects to provide a retainer in which the keys may be divided so as to assist in their identification or easy access.

Another object of the invention is to provide a key retainer upon which the keys may be easily and quickly positioned or removed from such position and yet when positioned securely retained in place.

Another object of the invention is to provide a retainer which will be ornamental and thus attractive in its appearance for sale.

Another object of the invention is to provide a retainer which will be exceedingly simple in its construction and one in which no soldering of the parts is necessary that skilled labor may be reduced to a minimum.

With these and other objects in view, the invention consists of certain novel features of construction, as will be more fully described, and particularly pointed out in the appended claims.

In the accompanying drawing:

Fig. 1 is a plan view showing the key retainer with two keys in position;

Fig. 2 is a view similar to Fig. 1 showing the closure member in section;

Fig. 3 is a section on line 3—3 of Fig. 1;

Fig. 4 is an edge view showing the relative movement of the closure member and the arcuate member;

Fig. 5 is a perspective view of one of the parts of the closure member;

Fig. 6 is a perspective view of another part of the closure member; and

Fig. 7 is a section on line 7—7 of Fig. 2 illustrating the manner of retaining the two relatively movable parts in clasped position.

Key retainers of the type carried by men either loose in the pocket or on the end of a chain are of various kinds and shapes and seek to accomplish different functional purposes; and while I attain some of the functional purposes strived at in

other key retainers, I do so by a different means and a different system of operation which lends for simplicity and inexpensive manufacture, yet attaining the desired results of ease and quickness in positioning keys on the retainer and security of keys while in position, while also attaining some additional advantages such as division of keys in the manner hereinafter set forth which has not heretofore been accomplished; and the following is a more detailed description of the present embodiment of this invention, illustrating the pre-

ferred means by which these advantageous results may be accomplished:

With reference to the drawing, 10 designates a wire of resilient character and preferably, although not necessarily, circular in cross section 5 bent into the generally arcuate form illustrated in Figs. 1 and 2. The end portions of the wire are bent inwardly to provide fingers 11 extending in generally parallel relation for the portion of their inwardly directed extent. These fingers are located diametrically opposite a straight portion 12 of the wire which provides a support about which the closure member may be pivotally mounted to be swung. This wire possesses a required resiliency so that the same when its end portions 11 15 are spread apart will move back into predetermined position again or tend to so move so as to grip any part which is located between the fingers.

One part of the closure member is shown perhaps best in Fig. 5 in perspective and is designated generally 14; it consists of a strip of sheet stock folded as at 15 to provide spaced arms 16, while the free ends of these arms are bent into semi-cylindrical formation as at 17 and provided with 20 lateral wings to embrace the straight support portion 12 and be pivotally mounted thereon. These cylindrical portions 17 are held so that their edges 18 abut and provide an inner diameter of sufficient extent so as to closely embrace and frictionally fit 25 upon the support 12, although allowing a pivotal movement with reference thereto. This relationship upon the support 12 is maintained by a clamp designated generally 19 consisting of a strap folded as at 20 with arms 21 extending along the outer surface of the closure member as shown in Fig. 3 with the lugs 22 folded inwardly about each arm 16 30 as shown in Figs. 2 and 4 so as to bind the closure member in the relationship shown in Fig. 3. This strap in addition to holding the ends of the closure 35 member together also provides a loop 24 for receiving a ring 25 to which a chain 26 may be attached for securing the retainer to the belt or other portion of the clothing of the wearer.

At the end of the closure where the bend 15 45 occurs, the width of the arms 16 is reduced as at 27 so that this width will be slightly greater than the normal width of the space between the fingers 11. Thus, when the closure member is swung to the closed position shown in Figs. 1, 2, 50 and 3, the round wire will serve as a wedge that it may be forced apart by the part 27 of the arms until one of the sheet metal arms passes part of the greatest diameter of the parallel fingers 11, and then these fingers will again spring toward 55

each other due to the resiliency of the member 10 so as to lodge between the arms at 27 as shown in Fig. 7 and thus hold the closure member firmly in its position as shown in Figs. 1, 2, and 3 to lock 5 any keys which may have been positioned along fingers 11 and moved along the arc of Fig. 10 against removal.

I provide two portions of a key retainer so that a key may be positioned either on one portion, as is the key 30, or on the other portion, as 10 the key 31. By having two separate portions each independent and completely separate from the other, I may arrange certain keys on one portion and other keys on other portions; or I may 15 arrange one or two keys on one portion and all the other keys in the other portion, thus to assist in the selection of keys for use.

The foregoing description is directed solely towards the construction illustrated, but I desire it 20 to be understood that I reserve the privilege of resorting to all the mechanical changes to which the device is susceptible.

I claim:

1. A key retainer comprising a resilient arcuate 25 member having spaced end portions, and a closure member hingedly mounted on said arcuate member at a location opposite said spaced end portions and swingable between and into engagement with said end portions to move said end portions apart as swung into closed position.

2. A key retainer comprising a resilient arcuate member having spaced parallel extending end portions, and a closure member hingedly mounted on said arcuate member at a location opposite said 30 spaced end portions and swingable between and into engagement with said end portions to move

said end portions apart as swung into closed position and be bound from accidental movement by the inherent spring of the stock of said end portions.

3. A key retainer comprising a resilient arcuate 5 member having spaced inwardly directed parallel extending end portions, and a closure member hingedly mounted on said arcuate member at a location opposite said spaced end portions and swingable between and into engagement with said 10 end portions to move said end portions apart as swung into closed position and be bound by the inherent spring of the stock of said end portions.

4. A key retainer comprising a resilient arcuate 15 member having spaced end portions, and a sheet metal closure member providing spaced arms hingedly mounted on said arcuate member at a location opposite said spaced end portions and having an end of a width greater than said portion to be swingable to position the end portions 20 of said member between said spaced arms by resiliently moving said end portions apart.

5. A key retainer comprising a resilient arcuate member having spaced parallel extending end portions, a sheet metal closure member folded upon 25 itself to provide spaced arms with portions of said arms embracing said member to pivotally mount the same thereon at a location diametrically opposite said spaced fingers, said closure member being swingable to a position between said parallel 30 fingers and of a width greater than the space between said fingers to resiliently urge said fingers apart and cause them to lodge between the arms of said closure member when the member is moved to closed position.

RENE M. SCHUPPACH.
